UNITED STATES PATENT OFFICE.

HARRY ROTH, OF DETROIT, MICHIGAN.

ADJUSTABLE FOLDING HORSE OR SCAFFOLD.

Application filed November 16, 1925. Serial No. 69,329.

My invention relates to an adjustable folding horse or scaffold, shown in the accompanying drawings and more particularly described in the following specification and 5 claims.

The primary object of this invention is to construct an adjustable folding horse for painters, paper-hangers or other artisans, adapted to support planks forming an elevated platform for workmen to stand upon which may be adjusted as required and when not in use may be folded into compact form for transportation.

A further object of the invention is to provide means for extending the inclined legs of the device whereby the platform can be raised to a relatively greater altitude than that provided by the main supporting legs—or the horses may be mounted upon an adjustable footing secured to the top of one or more pair of horses if preferred.

A further object of the invention is to provide the legs of the device with steps that workmen may readily ascend to the 25 platform or descend therefrom.

A further object of the invention is to provide telescoping members connecting the legs of the horse together, whereby they may be adjusted to a greater or less distance from 30 each other as required.

A further object of the invention is to provide means whereby the platform planks may be supported either longitudinally upon brackets secured to the legs of the horse, or 35 transversely upon the adjustable rails connecting the legs of the horse together, the opposite ends of the planks resting upon the adjustable rails of a like horse spaced from the first named horse.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification:

Figure 1 is a perspective view of the device showing a fragment of a platform plank in dotted lines resting upon brackets secured to the legs of the horse and extending parallel with the adjustable rails connecting said legs together—also a platform plank

resting upon said adjustable rails and extending transversely therefrom, to be supported at the other end by the adjustable bars of a like device—not shown.

60

Figure 2 is a fragmentary perspective view of a detail of construction showing means for securing the platform bracket to a leg of the device.

Figure 3 is a fragmentary perspective view showing the fixture connecting the upper end of the inclined legs of the device with the horizontal adjustable rail—in turn coupled with a like horizontal rail extending from a co-acting leg at the other end of the horse—not shown—the view showing the horizontal rail turned downwardly between the legs which are folded to lie against or in contiguous relation to said rail.

Figure 4 is an elevation of the device 75 showing one pair of legs and connecting rails in "knocked down" condition as when folded for shipment—the several elements being held together by a removable bolt, extending through said elements, fitted with a wing-nut to secure the parts against loss or displacement.

Figure 5 is a perspective view showing extension bars attached to the legs of the device to increase its altitude.

85

Figure 6 is a fragmentary perspective view of one of the horizontal adjustable rails and T-brace member pivoted thereto—the transverse bar of the T-brace being turned on its pivot to parallel the bar as when 90 "knocked down" for shipment, showing in dotted lines a clip member adapted to engage the step fittings.

Figure 7 is a fragmentary perspective view showing means for increasing the altitude of the device.

Referring now to the letters of reference placed upon the drawings:

A denotes an adjustable horse comprising a pair of inclined legs B, B, secured together at their upper ends by a divided fixture C, consisting of two opposing sheet metal planes C¹ adapted to overlap the ends of the legs and to embrace a normally horizontal telescoping member D, comprising a pair of adjustable rails D¹, D¹, pivoted respectively to the legs B, B, at each end of the horse by a transverse bolt E extending through the divided fixture fitted with a wing-nut E¹, whereby the parts may be rigidly secured together when properly adjusted.

100

105

110

The rails D^1 , D^1 , are held in telescopic relation by a pair of clips or clevises F , respectively secured to each of the rails—the bolt F^1 of each clevis overlapping the adjustment rail and extending through perforations in the opposing walls of the clevis—the bolts being fitted with wing-nuts F^2 , secured by chains F^3 , to the rails to insure against accidental loss of the nuts.

10 As shown in Figure 3 the horizontal rails D^1 —held between the divided fixture C by the bolt E —may be disconnected from each other and turned between, and parallel with the legs to which they are respectively secured.

15 G denotes a plurality of step-fittings secured to the legs at spaced intervals, having an outstanding portion G^1 , slotted as at G^2 , to receive the ends of a telescoping member H , comprising two rails H^1 , H^1 , held in coupled relation by a suitable socket fitting H^2 , H^2 .

20 J indicates in dotted lines one of a series of planks forming a platform resting upon the cross-members H^1 , of two horses of like construction.

25 The upper end of the outstanding portion G^1 is turned at right-angles, as indicated at G^3 , to provide a step for convenience in ascending or descending from the horse.

30 I designates an adjustable bracket fixture adapted to receive and support a plank J^1 . The bracket consists of a triangular shaped strap member secured to a U-shaped element I^1 ,

35 having a bayonet slot I^2 , which is designed to engage a bolt I^3 , projecting from the foot brackets G , whereby it is adapted to be secured to the legs at different altitudes. The bracket has a horizontal foot portion I^4

40 to receive a plank J^1 , and an upstanding end I^5 , designed to overlap the edge of the plank to secure the latter against accidental dislodgment.

45 K indicates a folding brace member pivoted to a lug secured to the rail D^1 , at its upper end and at its lower end there is pivoted a cross-bar K^1 slotted at each end to receive a bolt K^2 projecting from the walls of opposing foot brackets—the object being 50 to secure the inclined legs in their "spread" relation and to otherwise stiffen the structure when set up.

To provide means whereby the altitude of the device may be increased, suitable extension legs L , are fitted with cross-strips L^1 , designed to enter slots L^2 in the foot brackets G . When it is desired to employ the extension legs, they may be engaged to the lower ends of the legs B —as indicated in Figure 55—by coupling the same with any pair of the step brackets necessary to raise the device to the required altitude.

60 M denotes a connecting brace bar slotted at its ends to engage the bolts projecting from the edges of the auxiliary legs L , L .

In Figure 7 is shown other means for increasing the altitude of the device in which a pair of horizontal telescoping bars N , N , are supported upon the top of a pair of horses and secured against displacement by the overlapping L-shaped bracket N^1 , attached to the top of the horse and fitted with a thumb-screw N^2 , which when adjusted serves to bind the bars rigidly to the horse. Figure 7 shows a fragment of a pair of inclined legs N^3 , N^3 , each pivoted to a U-shaped bracket N^4 , in turn fastened to the bars N , mounted upon the legs B , B , of the horse A .

75 Having now indicated the several parts by reference letters the construction and operation of my device will be readily understood:

80 In setting up the horse the legs B , B , are spread apart at their lower ends and the thumb nuts E^1 adjusted to hold the upper ends of the legs securely to the horizontal telescoping member D . The cross-bar K^1 of the folding brace member K is then engaged with the bolts projecting from the step brackets G . The brackets I , at each end of the horse, are then adjusted to the proper altitude and secured—the bayonet slot of the U-shaped portion being engaged with the bolts I^3 , projecting from the step-brackets. The platform plank J^1 is then laid upon the brackets I —the steps G^3 integral with the brackets G forming convenient means for ascending to or from the platform.

85 If it is desired to raise the altitude of the horse it may be done by adding the extension legs L to the lower end of the legs of the horse—as previously indicated and shown in Figure 5—a connecting rod M , being engaged to the legs at their lower ends to keep them from spreading.

90 If desired auxiliary horses may be mounted upon bars secured to the top of the horses proper. This may be done by mounting extension bars N upon the top of the horse—securing them against dislodgment by the thumb screw N^2 —as clearly indicated in Figure 7. It is of course understood that the bars N are supported by a plurality of horses spaced apart.

95 When it is desired to fold up the framing for shipment the horizontal rails D^1 , D^1 , are disconnected and turned so as to lie between the legs at the respective ends of the device—as indicated in Figure 3—the legs being in turn swung contiguous to the bar D^1 , lying between them.

100 The wing-nut engaging the bolt E is not shown in Figures 3—as indicated in Figure 2—the nut being applied to the bolt on the opposite side of legs, thus permitting the attachment of the bracket I to the fitting C if desired.

105 Having folded the legs, the several elements are secured together in the manner

indicated—see Figure 4—by a bolt P extending through a hole bored through the several parts—the bolt being then engaged by a wing-nut P¹. In folding the bar D between the legs of the horse the cross-bar of the brace rod K is turned on its pivot parallel with the main portion of the brace, as indicated in Figure 6. When bundling the parts in their “knocked down” relation—as indicated in Figure 4—a U-shaped clip Q is inserted so as to overlap the brace K—extending between the brace and the edge of the step brackets of the respective end legs—the flanges Q¹ at the ends of the clip overlapping the step brackets, as shown in dotted lines in Figure 6. The device when in “knock down” form is ready for shipment or storage.

Having thus described my invention what I claim is:

1. In a device of the character described; a normally horizontal telescoping member comprising two rails adjustable with reference to each other; means for supporting said rails in alignment and in fixed relation to each other when adjusted; a pair of inclined legs pivoted to the outer end of each of said telescoping rails; a plurality of divided fixtures respectively adapted to embrace the upper ends of each pair of legs and one end of each of the telescoping rails; bolts extending through said divided fixtures to serve as pivots connecting the rails with said legs and to secure the parts in rigid relation to each other when adjusted; brackets secured to the legs at each end of the

device and having studs thereon; brace members pivoted to the rails of said first named horizontal telescoping member and to cross members having slots therein to engage the 40 studs on the brackets.

2. In a device of the character described including a horizontal rail and inclined legs secured thereto, a plurality of spaced brackets on the legs having slots therein to receive 45 the ends of an additional horizontal rail, each bracket having an offset portion terminating in a horizontal flange to form steps on the legs.

3. In a device of the character described, 50 a normally horizontal member, legs arranged in pairs at the ends of the member and supporting the same, brackets mounted on the legs and arranged in horizontal alignment and having projecting supporting portions provided with recesses, and an adjustable horizontal member having terminal portions adapted to fit in the recesses of the horizontally aligned brackets.

4. In a device of the character described, 60 a normally horizontal member, legs arranged in pairs at the ends of the member and supporting the same, a plurality of brackets on each leg, each having a slot therein, extensions for each leg, and a plurality of cross 65 strips on each extension, at least two of which are received by the slots in the brackets to secure the extensions to the legs.

In testimony whereof, I sign this specification.

HARRY ROTH.
